UNITED STATES PATENT OFFICE.

FRANCIS TRAVERS BIRDWOOD, OF LONDON, ENGLAND.

APPARATUS FOR THE EXTRACTION OF NICOTIN AND OTHER PRODUCTS FROM TOBACCO.

1,178,487.

Specification of Letters Patent. Patented Apr. 11, 1916.

Application filed July 1, 1915. Serial No. 37,500.

To all whom it may concern:

Be it known that I, FRANCIS TRAVERS BIRDWOOD, a subject of the King of England, residing in London, England, have 5 invented certain new and useful Improvements in Apparatus for the Extraction of Nicotin and other Products from Tobacco or Tobacco Products, of which the following is a specification.

10 This invention relates to improvements in apparatus for extracting, principally, nicotin and ammonia from tobacco and tobacco products, although other substances may also be removed from the tobacco or its 15 products in a similar manner.

The type of apparatus to which the present invention relates is that having a receptacle in which the tobacco or the like is heated up gradually to the required temperature in combination with a condensing or cooling surface for condensing the vapors distilled from the tobacco or the like and having means to conduct such condensed products away from the apparatus.

25 In the present apparatus the tobacco is preferably treated in a manufactured or usable condition such as, for instance, cigars, cigarettes, smoking mixtures and chewing tobacco.

30 According to this invention apparatus of the kind described is characterized by a condensing device comprising a member presenting a concave surface to the interior of the heating chamber and provided around

35 its lower edge with an annular trough having a discharge pipe leading from it to the outside of the casing for the removal of the condensed products which have accumulated in the trough. Preferably the construction

40 is such that the perimeter of the lower edge of the concave member is substantially equal to that of the heating chamber and the sloping sides of the former spring from the top edge of the latter.

45 A feature of the invention consists in a construction of apparatus of the kind first herein described having a heating chamber surrounded by a jacket across which are one or more partitions to divide it into two

50 or more compartments, means to conduct the heating fluid to each of the compartments so formed and means for the removal of waste

heating fluid therefrom through valve-controlled conduits.

The invention will be more readily understood by reference to the following description taken in connection with the accompanying drawings, in which—

Figure 1 is a section of a preferred construction of apparatus embodying the features of the present invention; Fig. 2 is a section on the line 2—2 of Fig. 1; Fig. 3 is a section of an alternative construction of tobacco-container; Fig. 4 is a longitudinal section through the heater diagrammatically shown in Fig. 1, and Fig. 5 is a section on the line 5—5 of the heater shown in Fig. 4.

The heating chamber comprises a cylindrical casing A closed at the bottom and open at the top. This is surrounded by a 70 cylindrical double-walled jacket spaced away therefrom, the two walls being shown at B and B¹ respectively. Between the two walls B and B¹ there may be either an air-space or the space so formed may be filled with a 75 heat-insulating material such as asbestos paste, silica wool or other desired lagging. The space between the cylinders A and B constitutes a heating jacket for the chamber A. Across the heating jacket so formed 80 are preferably two annular partitions C, C¹ so that the jacket is divided into three equal-sized chambers one above the other and to each of these chambers are led heated gases from a heater designated as a whole 85 by the reference character D to be described more particularly hereinafter.

The heated products of combustion, and in the preferred case heated air obtained by the draft through the heater, are led into a 90 box or trunk E, the interior of which trunk communicates with the compartments of the heating jacket through passages E¹ E² E³. The passages E¹ and E² are of comparatively small area while the passage E³ is of 95 considerably larger area and each of them, if desired, may be valve-controlled in any convenient manner as by means of sliding dampers diagrammatically shown at E⁴, E⁵ and E⁶.

Pipes F¹ F² F³ from each of the heating jacket compartments lead to a common uptake F for the removal of the cooled heating gases and each of the pipes is valve-con-

trolled by butterfly valves such as F⁴ or other convenient device.

The spaces at the upper and lower ends between the jacket and the heating chamber 5 are closed in any convenient manner preferably at the upper end by an annular plate A¹ while the ends of the passage formed between the cylinders B and B¹ are closed in a similar manner at the top, preferably by 10 an annular plate B².

The plates A¹ and B² are preferably lagged on their upper surfaces with asbestos or other heat-insulating material, not shown in the drawings, to prevent heat-radiation 15 through them. The exterior of the whole apparatus may be lagged also with any desirable heat-insulating material or such parts of it may be so lagged as found convenient or necessary.

20 Disposed immediately in front of each of the pipes or passages E¹ E² E³ is a screen of heat-insulating material, such as sheet asbestos, E⁷, which may be steadied or held in place in any convenient manner (not 25 shown in the drawings) and each screen E⁷ preferably extends for about one-third of the circumference of the apparatus. The purpose of the screens E⁷ is to distribute the heating medium entering through the passages E¹ E² E³ more evenly around the heating jacket. If the screens E⁷ are not provided, it is found that that portion of the casing A immediately in line with the passages E¹ E² E³ becomes too highly heated 30 as of course it will be readily understood that the heating fluid, at its greatest temperature, would impinge directly upon such parts of the casing A. In place of a heat-insulating screen, a metal gauze screen could 35 be provided which would also serve to distribute the heating fluid more evenly within the casing.

40 A condenser adapted to close the upper end of the heating chamber comprises a conical member G presenting a concavity to the interior of the chamber and having around its lower edge a trough G¹. Surrounding the member G is a receptacle H for the reception of a cooling fluid such as 45 water whereby the conical condensing surface of the member G is kept continually cool. A pipe G² leads from the trough through the side wall to the outside of the apparatus so that fluid which has condensed 50 on the surface of the member G and has run into and accumulated in the trough G¹ may be conducted from the trough to a convenient receptacle. The condenser and its surrounding water-jacket, as will be seen, form 55 the closure or cover of the apparatus and to this end a flange G³ is provided to rest upon the top of the apparatus.

60 The tobacco is preferably charged into receptacles which conveniently comprise cy-

lindrical sheet metal containers J having 65 flat perforated bases. Each receptacle is provided with supporting legs J¹ which conveniently rest upon ledges or projections extending inwardly from the sides of the casing A. Alternatively the legs of an 70 upper container may be supported by the edge of a container below it.

An alternative construction of containers 75 for the tobacco comprises cylindrical receptacles having conically-disposed bases generally imperforate, whose apices project into the interior of the containers. Around the lower edge of each of the conical bases may be formed a trough to catch any vapor which may condense on the lower side of the 80 conical base, having emanated from the tobacco contained in the receptacle below it. These containers are placed and supported in position, in a similar manner to that just described, one above the other.

85 As a further alternative construction, each container may be provided with a perforated false bottom situated within the cylindrical casing at the level of the apex of the conical base, and that portion of the side 90 wall of the casing extending between the false bottom and the lowermost edge may be slotted or apertured.

In another form, each cylindrical container may be provided with a flat perforated 95 or gauze bottom and about midway in its height is provided with another removable gauze or perforated tray, while in the side walls of the container below the latter tray are holes to permit of circulating air. Thus, 100 the container is divided into what is practically two containers in close proximity to one another.

105 Such a receptacle is illustrated in cross-section in Fig. 3, in which, as before, the container is referred to by the letter J, and the false bottom is shown at J⁴, while the perforations in the container-wall J are shown at J³, and the gauze bottom at J². In every case where perforated bases are required, such perforations may be provided by sheets of wire netting of fine mesh which form the bottoms or bases of the containers.

110 In Fig. 4 is shown a longitudinal section of the burner D which consists of a firebrick or other casing D¹ within which are disposed two horizontal burners D² having gas-outlets on either side as shown in Fig. 5. Above the burners are grids or slotted plates D³ preferably removable and supported on 115 channel bars D⁴. The air-entry end of the heater is baffled as to its upper portion at D⁵ and the air is only allowed to enter at D⁶ under the burners and under a baffle-plate D⁷ which helps in the distribution of the air 120 throughout the entire heater. The heated air is drawn away into the casing from the 125 upper portion of the opposite end of the

heater so that all the air entering the heating jacket A, B must pass through the heated grids D⁸.

At the bottom of the chamber an air-inlet 5 A² may be provided as shown in Fig. 1, conveniently valve-controlled, to assist in the circulation of air in the apparatus. When the tobacco-containers are of such a construction that they employ a trough around 10 and beneath the lower edges of their side walls, a small drip-cup may be provided conveniently detachably secured to the tobacco-container disposed below an orifice in the trough so that any condensed fluid collecting in the trough may pass through the 15 orifice into the drip-cup.

In operation the tobacco either as, for example, smoking tobacco or as cigarettes or as cigars, is packed into containers of the 20 required form which are then placed within the heating chamber one above the other. In the apparatus illustrated in the drawings, there are three of such containers. Heated air is then admitted to the heating jacket A, 25 B and the temperature of the interior of the heating chamber A is gradually raised to the required degree, varying, for example, as a maximum between 150° and 190° C. according to the character or quality of the 30 tobacco or product undergoing treatment.

The casing H surrounding the outer surface of the conical condenser G is filled with cold water and as the tobacco becomes heated the nicotin, ammonia and certain other 35 substances are driven off and condensed on the sloping sides of the condenser from which the condensed products flow into the annular trough G¹ to the discharge pipe G² leading to the exterior of the machine. The 40 temperature of the apparatus may be maintained equal throughout by the regulation of the dampers E⁴ E⁵ E⁶ and the valves F⁴ controlling the admission and exhaust of the heating fluid from the various compartments 45 of the heating jacket. Apertures are preferably provided for the insertion of a thermometer into the interior of the heating chamber at positions intermediate the partitions in the heating jacket so that the thermal 50 conditions inside the heating chamber may be continually observed.

Such an apparatus has many advantages, among which may be mentioned that the construction of condensing surface G is such 55 that all the products condense thereon and are conveyed to the trough G¹, that is to say, there is no comparatively cold surface upon which the vapors could condense which is not in communication with the 60 annular trough. Further, by the heating arrangements provided, the interior of the casing is uniformly heated and the tobacco does not become unduly heated or discolored at isolated portions. The internal tempera-

ture is easily regulated. The capacity of 65 the machine is high, as the interior space is utilized to its best advantage.

Although a preferred construction of apparatus has been described herein in detail, the invention is not limited to such details 70 as they may be varied provided always that the spirit of the invention is not departed from. For example, the treating chamber may be provided with an additional condensing surface at its lower extremity and 75 this condensing surface may be of any convenient formation, that is to say, either flat or slightly coned or pyramidal, the latter presenting either a convexity or a concavity 80 toward the interior of the chamber.

What I claim as my invention and desire to secure by Letters Patent is:—

1. Apparatus for the treatment of tobacco for the purpose described and comprising a chamber for the reception of the tobacco, 85 means to heat the chamber, a condensing device in communication with the chamber, said condensing device being in the form of a member presenting a concave surface to the interior of the chamber, a collecting 90 trough for the lower edge of said surface, and a discharge conduit for the trough.

2. Apparatus for the treatment of tobacco for the purpose described and comprising a chamber for the reception of the tobacco, 95 means to heat the chamber, a condensing device in communication with the chamber, said condensing device being in the form of a member presenting a concave surface to the interior of the chamber and having the 100 perimeter of its lower edge substantially equal to that of the heating chamber with its sloping sides springing from the open top edge of the said chamber, a collecting trough for the lower edge of said concave 105 surface, and a discharge conduit for the trough.

3. Apparatus for the treatment of tobacco for the purpose described and comprising a chamber for the reception of the tobacco, 110 means to heat the chamber, a conical or pyramidal condensing surface for the chamber presenting its concave surface to the interior of the latter, a collecting trough for the lower edge of the condensing surface, 115 and a discharge pipe communicating with the trough.

4. Apparatus for the treatment of tobacco for the purpose described and comprising a chamber for the reception of the tobacco, 120 means to heat the chamber, a conical or pyramidal condensing surface for the chamber presenting its concave surface to the interior of the latter and having the perimeter of its lower edge substantially equal to 125 that of the heating chamber with its sloping sides springing from the open top edge of the said chamber, a collecting trough for

the lower edge of said condensing surface, and a discharge pipe for the trough.

5. Apparatus for the treatment of tobacco for the purpose described and comprising a chamber for the reception of the tobacco, a heating jacket surrounding said chamber, means to divide the heating jacket into a plurality of separate compartments, means to heat each of the compartments so formed, 10 regulatable means for the removal of waste heat therefrom, means to condense the products distilled from the tobacco, and means to collect the condensate.

6. Apparatus for the treatment of tobacco 15 for the purpose described and comprising a chamber for the reception of the tobacco, a heating jacket surrounding said chamber, means to divide the heating jacket into a plurality of separate compartments arranged one above the other, means to heat each of the compartments so formed, regulatable means for the removal of waste heat therefrom, means to condense the products distilled from the tobacco and means to collect the condensate.

7. Apparatus for the treatment of tobacco for the purpose described and comprising a chamber for the reception of the tobacco, a heating jacket surrounding the said chamber, means to divide the heating jacket into a plurality of separate compartments, means to heat each of the compartments so formed, regulatable means for the removal of waste heat therefrom, a condensing device for the 30 chamber formed with a concave surface presented to the interior of the said chamber and provided around its lower edge with a trough, and a discharge pipe communicating with the said trough.

40 8. Apparatus for the treatment of tobacco for the purpose described and comprising a chamber for the reception of the tobacco, a heating jacket surrounding the said chamber, means to divide the heating jacket into a plurality of separate compartments, means to heat each of the compartments so formed, 45 regulatable means for the removal of waste heat therefrom, a condensing device for the chamber formed with a concave surface presented to the interior of the said chamber and provided around its lower edge with a trough, and a discharge pipe communicating with the said trough.

50 55 9. Apparatus for the treatment of tobacco for the purpose described and comprising a chamber for the reception of the tobacco, a heating jacket surrounding the said chamber, means to divide the said heating jacket into a plurality of separate compartments arranged one above the other, means to heat 60

each compartment so formed, regulatable means for the removal of waste heat therefrom, a condensing device for the chamber formed with a concave surface presented to the interior of the said chamber and provided around its lower edge with a trough, 70 and a discharge pipe communicating with the said trough.

10. Apparatus for the treatment of tobacco for the purpose described and comprising a chamber for the reception of the 75 tobacco, a heating jacket surrounding the said chamber, means to divide the said heating jacket into a plurality of separate compartments, arranged one above the other, means to heat each of the compartments so 80 formed, regulatable means for the removal of waste heat therefrom, a condensing device for the chamber formed with a concave surface presented to the interior of the said chamber and provided around its lower edge 85 with a trough, the perimeter of the lower edge of the concave member being substantially equal to that of the heating chamber with its sloping sides springing from the open top edge of the said chamber, and a 90 discharge pipe communicating with the said trough.

11. Apparatus for the treatment of tobacco for the purpose described comprising a heating chamber, a condensing device 95 formed with a concave surface presented to the interior of the heating chamber, a trough provided around the lower edge of the said surface, a discharge pipe communicating with the trough, and a plurality of tobacco-receptacles arranged one above the other 100 within the heating chamber.

12. Apparatus for the treatment of tobacco for the purpose described comprising a heating chamber, a condensing device 105 formed with a concave surface presented to the interior of the heating chamber, a trough provided around the lower edge of the said surface, a discharge pipe communicating with the trough, and a plurality of tobacco-receptacles arranged one above the other 110 within the heating chamber, each of the said receptacles having a perforated base.

13. Apparatus for the treatment of tobacco for the purpose described comprising a heating chamber, a condensing device 115 formed with a concave surface presented to the interior of the heating chamber, a trough provided around the lower edge of the said surface, a discharge pipe communicating 120 with the trough, and a plurality of tobacco-receptacles arranged one above the other within the heating chamber, each of the receptacles having a perforated base, a perforated false bottom separated therefrom 125 and side walls perforated in the part situated between the base and the false bottom.

14. Apparatus for the treatment of to-

16. Apparatus for the treatment of tobacco for the purpose described comprising, a tubular heating chamber, a plurality of tobacco-receptacles having perforated bases arranged one above the other in the heating chamber in the direction of its axis, a heating jacket surrounding said chamber and divided into a plurality of separate compartments one above the other, a fluid heater disposed outside the said heating jacket, means to conduct heated fluid into each of the compartments of the heating jacket, regulatable means to remove waste heating fluid from each of the compartments, a conical condensing surface arranged at the upper end of the chamber in communication therewith and presenting its concave surface

to the interior of the chamber, means to cool the exterior of the said conical surface, a trough around the lower edge of said surface arranged within the heating chamber, and a discharge pipe communicating with said trough. 65

17. Apparatus for the treatment of tobacco for the purpose described comprising, a tubular heating chamber, a plurality of tobacco-receptacles arranged one above the other in the heating chamber in the direction of its axis, a heating jacket surrounding said chamber and divided into a plurality of separate compartments one above the other, a fluid heater disposed outside the said heating jacket, means to conduct heated fluid into each of the compartments of the heating jacket, regulatable means to remove waste heating fluid from each of the compartments, a conical condensing surface arranged at the upper end of the chamber in communication therewith and presenting its concave surface to the interior of the chamber, a water-jacket surrounding the exterior of said conical surface, a trough around the lower edge of said surface arranged within the heating chamber, and a discharge pipe communicating with said trough.

18. Apparatus for the treatment of tobacco for the purpose described comprising, a tubular heating chamber, a plurality of tobacco-receptacles having perforated bases arranged one above the other in the heating chamber in the direction of its axis, a heating jacket surrounding said chamber and divided into a plurality of separate compartments one above the other, a fluid heater disposed outside the said heating jacket, means to conduct heated fluid into each of the compartments of the heating jacket, regulatable means to remove waste heating fluid from each of the compartments, a conical condensing surface arranged at the upper end of the chamber in communication therewith and presenting its concave surface to the interior of the chamber, a water-jacket surrounding the exterior of said conical surface, a trough around the lower edge of said surface arranged within the heating chamber, and a discharge pipe communicating with said trough.

In testimony whereof I have signed my name to this specification in the presence of two subscribing witnesses.
